HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA.

PITCH-COKING PROCESS.

Application filed August 31, 1921. Serial No. 497,373.

The invention relates to a process of coking pitch, for the production of substantially pure carbon suitable for electrodes and other useful purposes.

5 The coking of this substance has presented serious difficulties arising mainly from the boiling and foaming of the body of pitch when subjected to the necessary coking heat in the retort, so that it would leak 10 out past the retort doors or covers and rise up and clog or obstruct the gas passages leading from the upper part of the retort. Also the introduction of the pitch to be coked in a comparatively large body into the 15 highly heated retort, as heretofore produced, caused a chilling of the retort which resulted in the scaling off of the surfaces so exposed to heating and cooling, and also caused an undue expansion and contraction of the retort as a whole, the opening of the cracks 20 between the bricks, and the dropping out of the silica cement, and from one or all of these causes the retorts were rapidly deteriorated and injured, and silica as an objectionable impurity became mingled with the resulting coke, rendering the latter unsuitable for the intended uses of the same.

25 My invention obviates these difficulties by performing the coking of the pitch continuously, with a corresponding continuous introduction of the pitch in relatively small quantities at a time into the highly heated retort so that the chilling effect is so small, at any time, compared with the extent of the 30 retort and the high heat of the same that the described injuries cannot result. Nevertheless the pitch is fed into the retort with sufficient rapidity so that a body of substantially pure coke in quantity equal to the 35 capacity of the retort is produced without undue expenditure of time.

40 A pitch-coking retort of relatively large horizontal extent in proportion to the depth of the cooler liquid portion of the pitch which exists in the retort at any time is used for the process, so that an extensive surface of the pitch is exposed to receive the continuously incoming additional pitch, and the relatively cool pitch will touch the walls of 45 the retort for a very small depth, so that the chilling effect is negligible. Also there is an extensive horizontal surface of pitch to give off freely the distilling gases without excit-

ing bubbling or foaming or not to any considerable degree.

55 In accomplishing these useful results there is employed by preference a pitch-coking oven substantially such as is shown in the accompanying drawing, but this particular construction of oven is shown for the purpose 60 of illustration and explanation, and is not to limit the invention to the details of such construction, which may be varied without departure from the invention. In said drawings—

65 Figure 1 is a vertical cross section of the pitch-coking oven embodying the invention, on line I—I of Fig. 2.

70 Fig. 2 is a longitudinal vertical section of the same on line II—II of Fig. 1.

75 Fig. 3 is a front end view of the same, the oven door being removed.

80 Referring to the drawings, 1 indicates the oven structure, generally, the same being built of suitable material, and the upper parts which are to be subjected to high degrees of heat being composed of refractory material such as silica bricks or the like. The lower part of the structure comprises 85 regenerator chambers 2, 3, 4 and 5 which have the usual air and gas exits upward to the retort and which are to be used in the known alternating manner, so that the air and gas are heated to the combustion point in the previously used regenerator chambers 90 and the products of combustion pass down through and heat the regenerator chambers which are next to be used for the incoming air and gas.

95 In the upper part of the oven is constructed the retort 6 which is of an arched contour interiorly and is extended horizontally and sidewise to provide for the above described large superficial extent of the gradually introduced pitch. The lining 7 of this retort is made of silica brick and is highly refractory or sufficiently so for the coking heat to be raised.

100 After this retort has been heated to the degree requisite for coking pitch the latter is introduced in a small stream through the pipe 8, which is arranged at one end near the top of the retort, and the stream of liquid pitch is preferably caused to be of such force that it will be delivered or fall at a point 105 about midway between the two ends of the

retort. The gaseous matter resulting from the coking operation passes outward from the retort through the pipe 9.

In performing the said coking with this apparatus the retort is first raised to coking heat and until the limit of expansion has been substantially reached, and the liquid pitch is introduced as rapidly as may be under the condition that it must be raised to 10 the coking temperature without having any injurious chilling effect on the interior surface of the retort. This introduction of the pitch proceeds continuously as also does the coking operation, and the coked pitch accumulates in the retort until the capacity of 15 the same is reached, whereupon the feeding of the pitch is shut off. Thereafter the heating is continued to complete the coking of all parts of the charge, and further kept 20 at a high heat until the coke is completely calcined, that is, subjected to continuous high heat so that the entire charge is thoroughly coked and in a suitable condition for said uses, thus saving a separate calcining operation.

Thereafter the coke is removed in the usual manner, without interrupting the continuous heating of the retort; and after the retort doors have been again closed the same 30 continuous introduction of a further amount of pitch is proceeded with.

What is claimed is:—

1. A process of coking pitch, which comprises during the coking operation progressively introducing a coking charge by gradually accumulating a body of pitch and simultaneously coking it and gradually and continuously increasing the depth of the coking body of pitch by the addition of pitch 40 in liquid form to the top surface of said body, and at the same time proceeding with the coking operation.

2. A process of coking pitch, which comprises during the coking operation progressively introducing a coking charge by gradually accumulating a body of pitch and simultaneously coking it and gradually and continuously increasing the depth of the coking body of pitch by the addition of pitch 50 in liquid form to the top surface of said body, and at the same time proceeding with the coking operation, and then shutting off the supply of pitch and completing the coking of said body.

3. A process of coking pitch, which comprises during the coking operation progressively introducing a coking charge by gradually accumulating a body of pitch and simultaneously coking it and gradually and continuously increasing the depth of the coking body of pitch by the addition of pitch 60 in liquid form to the top surface of said body, and at the same time proceeding with the coking operation, and then shutting off the supply of pitch and completing the

coking of said body, and thereafter continuing the heating of said body until the coke is calcined.

4. A process of coking pitch, which comprises progressively introducing a coking charge by gradually accumulating a body of pitch and simultaneously coking it and continuing the introducing of liquid pitch into a highly heated coking retort gradually, in relatively small quantity at a time, and 75 continuously, and at the same time proceeding with the coking operation.

5. A process of coking pitch, which comprises progressively introducing a coking charge by gradually accumulating a body of 80 pitch and simultaneously coking it and continuing the introducing of liquid pitch into a highly heated coking retort gradually, in relatively small quantity at a time, and 85 continuously, and at the same time proceeding with the coking operation, and then shutting off the supply of pitch and completely coking that which has accumulated in the retort, and further heating said coke until it is calcined.

6. A process of coking pitch, which comprises progressively introducing a coking charge by gradually accumulating a body of pitch and simultaneously coking it, and applying thereon successive quantities of fluid 95 pitch of relatively small depth, and continuing and completing the coking of said pitch.

7. A process of coking pitch, which comprises progressively introducing a coking 100 charge by gradually accumulating a body of pitch and simultaneously coking it, and while the same is being coked applying thereon successive quantities of fluid pitch of relatively small depth, and continuing and 105 completing the coking of all of said pitch.

8. A process of making pitch coke from pitch in a coking chamber of a coking retort oven having heating walls on two opposite sides of said chamber provided with combustion flues and having regenerators below said coking chamber and heating walls communicably connected with said combustion flues, comprising: introducing pitch into said coking chamber while said chamber is being 110 highly heated; accumulating said pitch in a shallow body on the bottom of said chamber and simultaneously coking said body while thereon; gradually increasing the depth of said shallow body by gradual addition of further pitch to the top surface 115 of said body and at the same time proceeding with the coking operation.

9. A process of making pitch coke from pitch in a coking chamber of a coking retort 125 oven having heating walls on two opposite sides of said chamber provided with combustion flues and having regenerators below said coking chamber and heating walls communicably connected with said combustion flues,

comprising: introducing pitch into said coking chamber while said chamber is being highly heated; accumulating said pitch in a shallow body on the bottom of said chamber and simultaneously coking said body while thereon; gradually increasing the depth of said shallow body by gradual addition of further pitch to the top surface of said body and at the same time proceeding with the coking operation; then discontinuing the addition of further pitch to said body and completing the coking of said body.

10. A process of making pitch coke from pitchy material in a coking chamber of a coking retort oven having heating walls on two opposite sides of said chamber provided with combustion flues and having regenerators below said coking chamber and heating walls communicably connected with said combustion flues, comprising: introducing pitchy material into said coking chamber while said chamber is being highly heated; accumulating said pitchy material in a shallow body on the bottom of said chamber and simultaneously coking said body while thereon; gradually increasing the depth of said shallow body by gradual addition of further pitchy material to the top surface of said body and at the same time proceeding with the coking operation.

11. A process of making pitch coke from pitchy material in a coking chamber of a coking retort oven having heating walls on two opposite sides of said chamber provided with combustion flues and having regenerators below said coking chamber and heating walls communicably connected with said combustion flues, comprising: introducing pitchy material into said coking chamber while said chamber is being highly heated; accumulating said pitchy material in a shallow

body on the bottom of said chamber and simultaneously coking said body while thereon; gradually increasing the depth of said shallow body by gradual addition of further pitchy material to the top surface of said body and at the same time proceeding with the coking operation; then discontinuing the addition of further pitchy material to said body and completing the coking of said body.

12. A process of making pitch coke from pitchy material in a coking chamber of a coking retort oven, comprising: introducing pitchy material into said coking chamber while said chamber is being highly heated; accumulating said pitchy material in a shallow body on the bottom of said chamber and simultaneously coking said body while thereon; gradually increasing the depth of said shallow body by gradual addition of further pitchy material to the top surface of said body and at the same time proceeding with the coking operation.

13. A process of making pitch coke from pitchy material in a coking chamber of a coking retort oven, comprising: introducing pitchy material into said coking chamber while said chamber is being highly heated; accumulating said pitchy material in a shallow body on the bottom of said chamber and simultaneously coking said body while thereon; gradually increasing the depth of said shallow body by gradual addition of further pitchy material to the top surface of said body and at the same time proceeding with the coking operation; then discontinuing the addition of further pitchy material to said body and completing the coking of said body.

HEINRICH KOPPERS.
